DESIGN FOR A SUGAR BOWL OR SIMILAR ARTICLE

Vincent Broomhall and Herbert A. Smith, East Liverpool, Ohio, assignors to The Salem China Company, Salem, Ohio, a corporation

Application March 8, 1935, Serial No. 55,792

Term of patent 3½ years

To all whom it may concern:

Be it known that we, Vincent Broomhall and Herbert A. Smith, citizens of the United States, residing at East Liverpool, county of Columbiana, and State of Ohio, have invented a new, original, and ornamental Design for a Sugar Bowl or Similar Article, of which the following is a specification, reference being had to the accompanying drawing, forming a part thereof.

Fig. 2 is a top plan view of same with the cover in place;

Fig. 3 is a side elevational view of the sugar bowl with the cover removed; and

Fig. 4 is a top plan view of same with the cover removed.

What we claim is:

The ornamental design for a sugar bowl or similar article, as shown and described.

VINCENT BROOMHALL.
